DAMPER CONTROL

Arthur D. Cole, Minneapolis, Minn.

Application March 28, 1934, Serial No. 717,733

9 Claims. (Cl. 236—45)

My invention relates to damper controls and particularly to a control which may be utilized as a draft regulator.

Another object of the invention resides in providing a damper control operated through a separate pressure responsive device connected with the smoke pipe in which the damper is installed.

A still further object of the invention resides in providing a draft regulator by means of which 10 the draft in the smoke pipe of a heating plant may be regulated without admission of air from the exterior and into the smoke pipe.

An object of the invention resides in providing a draft regulator in which the regulation 15 of the draft is procured by throttling the flow of flue gases passing through the smoke pipe.

Another object of the invention resides in providing a damper control utilizing a vane operable in a manner similar to a piston and cylinder and controlling the operation of the 20 damper.

An object of the invention resides in providing a case disposed adjacent the pipe in which the damper is situated, said case having a chamber 25 therein communicating at one locality with the pipe and at another locality with the exterior and in which the vane is movable.

Another object of the invention resides in constructing said case with a circular wall and with 30 segmental walls and in pivoting said vane to said case at the axis of said circular wall, said vane extending across the space between said walls and substantially closing communication between the exterior and the passageway in said pipe.

An object of the invention resides in providing 35 a shaft extending into the chamber in said case and in supporting both said damper and said vane from said shaft.

A still further object of the invention resides in providing a frame extending about said pipe and case for supporting said case relative to said pipe.

40 A feature of the invention resides in providing said frame with bearings in which said shaft is journaled.

An object of the invention resides in constructing the damper control as a single unit 45 capable of being applied to a smoke pipe after erection of the smoke pipe and without the necessity of substituting a new length of pipe for any of the existing lengths of pipe.

Other objects of the invention reside in the 50 novel combination and arrangement of parts and

in the details of construction hereinafter illustrated and/or described.

In the drawings:

Fig. 1 is an elevational view of a boiler and smoke pipe therefor illustrating an embodiment 5 of my invention applied thereto.

Fig. 2 is a perspective view of a part of the smoke pipe shown in Fig. 1 with the damper control applied thereto.

Fig. 3 is an elevational view of the structure 10 shown in Fig. 2.

Fig. 4 is an elevational sectional view similar to Fig. 3 and taken on line 4—4 of Fig. 2.

Fig. 5 is a plan sectional view taken on line 15 5—5 of Fig. 4.

Fig. 6 is a cross sectional view taken on line 6—6 of Fig. 2.

Fig. 7 is a fragmentary elevational sectional view taken on line 7—7 of Fig. 3 and drawn to a larger scale.

Fig. 8 is a view similar to Fig. 2 of a modification of the invention.

Fig. 9 is a cross sectional view taken on line 9—9 of Fig. 8 and showing the parts in altered position.

Where heating plants are heated by oil or gas varying draft conditions cause improper combustion with the result of marked inefficiency. Regulation of draft has been attempted through pressure responsive devices admitting air into the smoke pipe, but such devices have certain undesirable characteristics. In the first place heated air from the building in which the heating plant is installed is utilized which causes loss of heat from the building as well as the 35 cooling of the stack. Secondly, such devices do not function the same under all draft conditions and accurate control hence cannot be had. The present invention provides a device by means of which the draft may be regulated through the 40 control of a damper without admission of air to the smoke pipe from the room in which the heating plant is installed and in which accurate regulation may be procured regardless of draft conditions.

For the purpose of illustrating my invention, I have shown in Fig. 1 a hot water boiler 10 of ordinary construction. This boiler is installed in a building having a basement 1 and a room 8 to be heated, said boiler being situated in the 50 basement. The first floor of the building is designated by the reference numeral 9 and includes the usual joists 32.

The boiler 10 comprises the usual fire pot section 11, an ash pit section 12 and a dome 13. 55

The fire pot section 11 is constructed with a fire door 14, a slice door 15 and the ash pit 12 is constructed with an ash door 17. The dome 13 is provided with a smoke outlet 18 to which the usual smoke pipe 19 is attached, which smoke pipe leads to the chimney of the building in which the heating plant is installed. Inasmuch as the construction of the boiler and the method of connecting the same to the radiators of the building forms no particular feature of the invention, the same have not been disclosed in this application. However, it can readily be comprehended that any suitable method may be used for installing the boiler and the same may be employed in any of the various heating systems such as are now in common use.

For further illustrating the application of my invention, I have shown the boiler as fired through a gas burner 20 which is provided with a gas pipe 21 for feeding fuel to the same and with a fuel pipe 22 delivering the fuel mixture into the fire pot of the boiler. The gas pipe 21 is provided with a valve 23 by means of which the flow of gas to the burner can be controlled for the purpose of maintaining the temperature of the room 8 constant.

For controlling the operation of the boiler 10 a thermostat 24 is employed which is installed in room 8 and which is connected by three wires 25 with a suitable heat regulator 26. Heat regulator 26 is merely illustrated diagrammatically though it can readily be comprehended that any suitable type of regulator may be employed. The form of heat regulator illustrated includes two cranks 27 and 28 which are adapted to be rotated through 180 degrees during each operation of the thermostat 24. Said regulator is provided with a base 31 and is supported through said base in the following manner: Attached to one of the joists 32 of the floor 9 of the building in which the heating plant is installed is a board 33 which projects downwardly past the smoke pipe 19. This board is provided near its lower end with a shelf 34 which is supported on said board through brackets 35. The base 31 of heat regulator 26 rests upon the shelf 34 and is secured thereto in any suitable manner.

The crank 28 of heat regulator 26 is connected through a chain or cord 29 with a lever 30 on the valve 23 by means of which said valve may be operated when the crank 28 rotates. When the crank 28 is in the position shown in Fig. 1, valve 23 is open and gas is being supplied to the burner 20. When the crank 28 is rotated to its opposite position, valve 23 is closed and the burner is shut off.

The form of my invention shown in Figs. 1 to 7 includes a length of pipe 36 which is installed in the smoke pipe 19 and which takes the place of one of the usual lengths of pipe ordinarily employed in said smoke pipe. The passageway through this pipe is designated by the numeral 40. The length of pipe is provided near its center with a laterally extending opening 37. A case 38 is attached to said pipe and is formed upon the interior thereof with a chamber 39 which communicates with the passageway 40 in pipe 36 through the opening 37. Case 38 is provided with a semi-circular portion 41 constructed with a semi-circular outer wall 42 and segmental end walls 43 and 44 connected to said circular wall. The end walls 43 and 44 are provided with flanges 45 by means of which the said end walls may be attached to the circular wall 42. The portion 41 of case 38 is arranged vertically as shown in Figs.

2 and 3 and the upper portion thereof, designated at 46, is left open. The lower part of the case is constructed with a conduit 47 which is connected to the pipe 36 and which brings the chamber 39 into communication with passageway 40 through the opening 37. This conduit consists of upper and lower walls 48 and 49 and an end wall 50. These various walls extend up to the circular portion 41 of the case and also up to the pipe proper and are attached thereto through screws 85.

For the purpose of holding the case 38 securely attached to the pipe section 36, a frame 51 is employed. This frame is constructed of a bar of iron bent in the form of a rectangle to provide upper and lower reaches 52 and 53 and end reaches 54 and 55 connected thereto. The ends of the frame 51 may be spliced along either of the reaches 52 or 53 and may be welded or otherwise secured together. The reach 52 extends across the upper portion of the pipe 36 and the case 38. This reach of the frame is attached to the upper edge of the circular wall 42 of portion 41 of case 38 through screws 56. Said reach is similarly attached to the pipe section 36 through a screw 57. The reach 53 of frame 51 is likewise attached to the lowermost portion of the circular wall 42 of case 38 through screws 58 and to the lowermost part of the pipe section 36 through a screw 59. By means of these screws the frame 51 is rigidly secured to the structure 30 forming the case 38 and the pipe section 36 and the said parts are securely held together.

It will be noted that the reach 55 of frame 51 is spaced from the end wall 43 of portion 41 of case 38. This is for a purpose to be presently described in detail. The two reaches 54 and 55 of frame 51 have secured to them bearings 60 and 61 which are provided with threads 62 threaded into the said reaches. Bearing 61 is shown in detail in Fig. 7 and is provided at its inner end with a conical socket 63. A shaft 64 extends through the passageway 40 in pipe section 36 and chamber 39 in case 38, the said shaft being provided at its ends with conical trunnions 65 journaled in the sockets 63 of bearings 60 and 61. By means of this construction the shaft 64 is supported for swinging movement and in a manner to involve a minimum amount of friction.

Within the passageway 40 of pipe section 36 is disposed a damper 66 which consists of two semi-circular sheets of metal 67 and 68 arranged in overlying position at the diametral edges thereof. The marginal portions of said sheets of metal at the diagonal edges are provided with grooves 69 which receive the shaft 64 and are bolted together through bolts 70 to hold the two parts of the damper in proper position and to securely attach the same to the shaft 64. By rotating the shaft 64 the damper 66 may be brought to a position such as shown in Fig. 6 in which the passageway 40 through the smoke pipe 36 is open or the same may be turned through angular positions as shown in Fig. 3 until the said damper completely obstructs the flow of gas through said smoke pipe.

The shaft 64 extends along the inner edge of the wall 48 of conduit 47 of case 38 and lies parallel with the reach 52 of frame 51 and is also disposed along the axis of the circular wall 42 of the portion 41 of said case. The shaft has attached to it a vane 71 constructed of sheet metal, which vane is best shown in Fig. 4. Vane 71 is provided at its inner end with a part 72 bent around the shaft 64 and clamped to said shaft through bolts 73 which pass through the

adjacent parts of said vane. The vane 71 fits snugly between the end walls 43 and 44 of the portion 41 of case 38 and also follows along the wall 42 of said portion of the case when the shaft 64 is rotated. The dimensions of the vane 71 are such that the edges of the said vane at all positions clear the various walls of the case in which the same is situated and so that a minimum amount of space exists between the 5 edges of said vane and said walls. It can readily be comprehended from Fig. 4 that one surface of the vane 71 is exposed to the exterior through the opening 46 in the portion 41 of case 38 and that the other surface of said vane is exposed 10 to the passageway 40 through the passageway in the conduit 47 and the chamber 39 in the portion 41 of case 38. Vane 71 operates in the manner of a piston, the portion 41 of case 38 serving as a cylinder and may travel from one position to the other within said cylinder as illustrated in 15 the various views of the drawings. By properly counterbalancing the vane and damper the said vane can be caused to move within the portion 41 of case 38 through variations in pressure occasioned by variations in the draft in the passageway 40 of the smoke pipe 19.

On the end of the shaft 64 and between the end wall 43 of the case and the reach 55 of frame 51 is provided a sheave 74 which is constructed 20 with a boss 75. A set screw 85 is screwed into this boss and serves to hold the sheave 74 attached to the said shaft. The boss 75 is further threaded to receive a rod 76 which extends outwardly therefrom. This rod is also threaded at the 25 outer end thereof and has screwed upon it a counter-weight 77 by means of which the weight of the vane 71 may be counterbalanced. Attached to the sheave 74 is a cord or chain 78 which is provided at its lower end with a hook 79. A weight 80 may be secured to the end of the cord 30 78 through the hook 79. By the selection of the proper weight, any desired draft can be 35 procured.

The operation of the invention is as follows: 40 When a certain draft is desired, a weight of suitable dimensions is placed on the hook 79. If the suction within the portion of the passageway 40 in advance of damper 66 increases beyond the degree for which the weight 80 is selected, then the said suction causes the vane 71 to move 45 from its position shown in Fig. 4 to an intermediate position, such as shown in Fig. 3. This causes the rotation of the damper 66. The damper 66 on being moved toward closing position, throttles the flow of flue gases through the smoke pipe 19 and thereby reduces the suction in the said pipe, in advance of the damper. As soon as the desired draft has been procured 50 suction on the inner surface of the vane 71 is equalized through the weight 80. If the draft decreases, then the weight 80 pulls the vane 71 back to such a position that the throttling effect of the damper 66 is sufficiently reduced to allow sufficient flue gas to pass through the smoke pipe. 55 When this occurs the desired degree of draft is reestablished. In this manner, the draft in the smoke pipe is maintained constant and is automatically adjusted regardless of the draft in the chimney to which the smoke pipe is connected. 60 In the type of gas burner illustrated, the valve 70 23 is used to control the fuel supply to the burner in accordance with the temperature of the room in which the thermostat 24 is situated. When the burner is shut down it becomes desirable to completely close the damper 66 to prevent the flow 75

of cold air through the boiler and the resultant loss of heat. For this purpose the crank 21 of the heat regulator is utilized which is set at the same position as the crank 28. This crank has attached to it a cord or chain 81 which is attached to the sheave 74 and which passes over said sheave on the opposite side thereof to the cord 78. When the heat regulator 26 operates in a manner to close the valve 23, the damper 66 is also closed and the flow of air through the 10 smoke pipe prevented.

In Figs. 8 and 9 I have shown the damper and the damper control as a single unit which may be applied to a smoke pipe after the same has been erected and without removing or replacing any of 15 the lengths of pipe thereof. This device will now be described in detail.

The construction shown in Figs. 8 and 9 includes a case 85 which is formed upon the interior thereof with a chamber 86. Case 85 is constructed 20 with segment shaped end walls 87 and 88 and with a curved wall 89 connected to said end walls. Said case is open at the top as indicated at 90. At the forward part of case 85 is provided a duct 91 formed with a passageway 92 within the same 25 which passageway communicates with the chamber 86 in said case. Duct 91 is constructed with a front wall 93, a rear wall 94 and with a top 95 and a bottom 96 connected thereto. One end of the duct 91 is left open as indicated at 98 and 30 is connected to the smoke pipe 19 of the boiler communicating therewith through an opening 99 in said smoke pipe. The other end of said duct is closed through an end wall 97 which in the form of the invention shown lies in continuation 35 of the end wall 88 of said case 85.

The front wall 93 and the rear wall 94 of duct 91 are cut curved as designated at 100 to fit about the exterior of the smoke pipe 19. To provide suitable bearing surfaces at such localities, 40 flanges 101 are provided which extend outwardly from said walls at the outer ends thereof. A strap 102 is used for attaching the case 85 to the smoke pipe 19. This strap extends about 45 the pipe 19 and is attached at its ends to the ends of the top 95 and bottom 96. For this purpose the lower end of strap 102 is provided with an eye 103. A tongue 104 formed on the end of the bottom 96 is hooked into this eye and bent back as shown in Fig. 9 to hold the strap securely attached to case 85 at the lower end of the strap. The upper end of the strap is bent to form a flange 105 extending outwardly therefrom. An angle 106 constructed with an outwardly extending flange 107 is attached to the 50 end of the top 95 of duct 91 through rivets 108 which pass through the other flange 109 of said angle. The flanges 105 and 107 lie in spaced relation when the device is assembled upon the smoke pipe. By means of a bolt 110 which extends through both of said flanges the two flanges are brought together and the band 102 drawn taut about the pipe 19 to securely attach the 55 entire device to the smoke pipe.

My invention further includes a damper 111 which is disposed within the smoke pipe 19 and a vane 112 which is disposed within the chamber 86 of case 85 and which latter functions through variation in suction in the pipe 119 to operate the damper 111. These parts are supported as 60 follows:

Upon the exterior of case 85 and attached to the end wall 88 thereof is a U-shaped frame member 113, one leg 114 of which is attached to the said wall 88 of the case. This is accom- 75

plished through rivets 115. The other leg 116 of said frame is spaced from the wall 88. Upon the interior of the end wall 87 of case 85 is attached a bearing bar 117 which is formed with a conical socket 118 situated at a locality coincident with the center of curvature of the curved wall 89 of said case. A shaft 118 is formed with conical ends 119 and 120, the end 119 being pivoted in the socket 118. The conical end 120 of this shaft is journaled in a socketed bearing 121 screwed into the leg 116 of frame 113. The shaft 118 extends through the other leg 114 of said frame and through the end wall 88 of the case 85. The vane 112 previously referred to is attached to this shaft which is accomplished in the same manner as the attachment of the vane 71 to shaft 64. The said vane is provided with a portion 72 which is bent around the shaft and which is clamped to the vane proper through 20 bolts 122.

The damper 111 is constructed from a single piece of sheet metal cut to the desired form. This damper is attached to the vane 112 through a U-shaped attaching member 123 which is constructed with two arms 124 and 125 and a connecting portion 126. Both the arms 124 and 125 are offset as indicated at 127, the arm 124 being attached to the damper 111 by rivets 128 and the arm 125 being attached to the vane 112 through 30 bolts 129. The connecting part 126 of the member 123 is so disposed as to lie in close proximity to the axis of the shaft 118 whereby the same when the vane 112 is oscillated may travel in the passageway 96 of duct 91 and may extend 35 through the opening 99 of smoke pipe 19 and into the passageway therein. It will thus be seen that the damper 111 is supported through the vane 112 and through a structure which is movable within the passageway in the duct 91 40 and which requires no support from the smoke pipe proper. Upon the shaft 118 and between the two legs 114 and 116 of the bracket 113 is disposed the sheave 74 and counter-weight 77 which function the same as the corresponding 45 parts of the other form of the invention.

The method of installing my invention is as follows: The opening 99 is first cut in the smoke pipe, which opening extends circumferentially about the pipe for a distance somewhat less than one-half the circumferential extent thereof. This opening is of a width substantially equal to the distance between the front and rear walls 93 and 94 of the duct 91. After the hole has been cut the device is arranged with the 50 damper 111 extending vertically which can be accomplished by exerting pressure upon the vane 112. The said damper is then inserted into the smoke pipe through the opening 99. After the damper is in position within the smoke pipe strap 102 is applied and the bolt 110 placed through the two flanges 105 and 106 and the nut thereof tightened to draw the parts together and to hold the entire control device securely attached to the smoke pipe. The connection of the cords 55 or chains associated with sheave 74 is thereafter made and the device will function in identically the same manner as the device previously described.

My invention is highly advantageous in that 60 an extremely simple and practical device is provided whereby a damper may be operated through pressure responsive means in an extremely simple and positive manner. When the device is used as a draft regulator, no air flows 65 from the exterior into the smoke pipe thereby

economizing on the amount of fuel used for heating purposes. The device when once set operates automatically and requires no further attention, there being no delicate or complicated parts to get out of adjustment. Different degrees of draft 5 may be procured by simply exchanging the weight on the damper shaft. The same damper that is used for controlling the draft may also be used for completely shutting off the draft when the gas or oil burner is shut off. 10

Changes in the specific form of my invention, as herein disclosed, may be made within the scope of what is claimed without departing from the spirit of my invention. 15

Having described my invention, what I claim as new and desire to protect by Letters Patent is:

1. In combination with a smoke pipe having a slot therein formed with parallel circumferential edges, a case having two spaced parallel walls formed with circular edges of the same diameter as the pipe and adapted to engage the pipe upon the exterior thereof and outwardly of the circumferential edges of the slot, means extending about said pipe and engaging said case for holding the case attached to the pipe, a damper within the pipe, a movable vane within the case, and means connecting said damper with said vane so that said damper is operated by said vane. 20

2. In combination with a smoke pipe having a slot therein formed with parallel circumferential edges, a case having two spaced parallel walls formed with circular edges of the same diameter as the pipe and adapted to engage the pipe upon the exterior thereof and outwardly of the circumferential edges of the slot, said case further having walls disposed between said last named walls and at right angles thereto, means extending about the pipe and issuing from said last named walls for holding the case attached to the pipe, 40 a damper within the pipe, a movable vane within the case, and means connecting said damper with said vane so that said damper is operated by the vane. 35

3. In combination with a smoke pipe having a narrow circumferential slot therein, a case, a neck connected to the case and provided with closely spaced parallel walls adapted to lie in close proximity to the edges of said slot, a movable vane mounted in said case and a pivoted damper disposed within the smoke pipe and partly within the limits of said neck and means connecting said damper and said vane so that said damper is operated by said vane, said damper being movable in one position parallel with the parallel walls of the neck to facilitate insertion of the damper into the smoke pipe through said slot. 50

4. In combination with a smoke pipe having an opening therein, a unitary draft regulator for application to the smoke pipe, said regulator comprising a case, a movable vane within said case, a neck connected to said case, said neck having two walls formed with arcuate edges adapted to fit against the smoke pipe, said neck covering the opening in the smoke pipe, and a circular damper disposed within said smoke pipe in proximity to said neck and supported for movement relative thereto, the circular edge of said damper being substantially concentric with the arcuate edge 60 of one of said walls when the damper is in one position, and means connecting said damper with said vane so that said damper is operated by said vane. 65

5. In combination with a smoke pipe having an 70

opening therein, a unitary draft regulator for application to the smoke pipe, said regulator comprising a case, a movable vane within said case, said case having a part constructed with two walls 5 formed with arcuate edges adapted to fit against the smoke pipe and cover the opening in the smoke pipe, and a circular damper disposed within said smoke pipe in proximity to said part of the case and supported for movement relative thereto, the circular edge of said damper being substantially concentric with the circular edge of one of said walls when the damper is in one position, and means connecting said damper with said vane so that said damper is operated by 10 said vane.

6. In combination with a cylindrical pipe having a semi-circular opening therein and formed with parallel circumferential edges bounding said opening and with edges extending along substantially diametrically opposed elements of said pipe and also bounding said opening, a draft regulator including a case having a part adapted to fit about the pipe and covering said opening, a damper disposed within said smoke pipe in proximity to said part and projecting outwardly therefrom, said damper being supported for movement relative to the case, and in one position being parallel with the planes of the circumferential edges of the opening in the pipe and disposed 25 between the same for facilitating insertion of the damper into the pipe, and means for holding the case attached to the pipe.

7. In combination with a cylindrical pipe having a semi-circular opening therein and formed with parallel circumferential edges bounding said opening and with edges extending along substantially diametrically opposed elements of said pipe and also bounding said opening, a draft regulator including a case having a part adapted to 30 fit about the pipe and covering said opening, a shaft pivoted in said case and extending diametrically of the pipe, a damper disposed in proximity to said part of the case and extending outwardly therefrom, said damper being supported

by said shaft, a vane in said case subject to the pressure in said pipe, and means for connecting said vane to said shaft so that said damper is operated by said vane.

8. In combination with a cylindrical pipe having a semi-circular opening therein and formed with parallel circumferential edges bounding said opening and with edges extending along substantially diametrically opposed elements of said pipe and also bounding said opening, said last named edges being shorter than the diameter of the pipe, a case, a neck issuing from the case and attachable to the pipe in a manner to cover said opening, said neck issuing from one side of the case, said case overlying the neck and being spaced 15 therefrom, a damper extending outwardly from said neck and into the pipe, said damper being insertable into the pipe through said opening, and a vane in said case, and means connecting said damper with said vane so that said damper 20 is operated by said vane.

9. In combination with a cylindrical pipe having a semi-circular opening therein and formed with parallel circumferential edges bounding said opening and with edges extending along substantially diametrically opposed elements of said pipe and also bounding said opening, said last named edges being shorter than the diameter of the pipe, a draft regulator including a case having a part adapted to fit about the pipe and 30 covering said opening, a damper disposed within said smoke pipe in proximity to said part and projecting outwardly therefrom, said damper being supported for movement relative to the case and in one position being parallel with the planes 35 of the circumferential edges of the opening in the pipe and disposed between the same, said second named edges of the opening being spaced apart a distance not less than the diameter of the damper, whereby the damper may be inserted 40 into said opening while the pipe is in position, and means disposed exteriorly of the pipe for holding the case attached to the pipe.

ARTHUR D. COLE.
